UNITED STATES PATENT OFFICE.

HENRY PLATT HALL, OF OLDHAM, ENGLAND.

CARRIAGE FOR SELF-ACTING MULES.

Application filed February 22, 1921. Serial No. 446,984.

To all whom it may concern:

Be it known that I, HENRY PLATT HALL, a subject of the King of the United Kingdom of Great Britain and Ireland, and resident of "Toravon" Werneth, Oldham, in the county of Lancaster, England, have invented new and useful Improvements in Carriages for Self-Acting Mules, of which the following is a specification.

10 This invention relates to carriages for self acting mules whether constructed wholly or in great part of steel or other metal plate or sheet or of wood and consists in the provision of plates of steel or 15 other suitable metal riveted to the fronts of sections of such carriages or the fronts of such carriages to extend vertically thereon and furnished with rearwardly extending top flanges serving in the completed 20 carriages as rests for the spindle rails or spindle boxes so that by plates of different heights being provided for use, an inclined flange may be provided at any height requisite in a section or carriage and it is made 25 easy to replace one plate by another, if after a carriage has been constructed it is necessary or desirable to provide a flange at a different height for spindles of different length to be used or change of the position 30 of the spindles.

This invention is illustrated by the accompanying drawing as applied in a carriage for a self acting mule constructed of sheet or other metal plate or sheet in the form of sections constituting when connected a continuous box girder as described in the specification of another application filed on the same day as this.

In the accompanying drawing, Fig. 1 is 40 a transverse section through part of the carriage of a self acting mule showing in side elevation one of the bearing brackets for the tin roller shaft and means for securing in position the bearing bracket shown and Fig. 45 2 is a front elevation illustrating parts at and near the junction of two sections of portions of the length of the carriage.

Fig. 3 is a detail section illustrating a jogged spindle rail rest riveted to the front 50 wall of a section of a carriage, and

Figs. 4 and 5 are detail sections illustrat-

ing two forms of jogged spindle rail rests.

The same letters of reference are employed to indicate corresponding parts in the figures. The mule carriage, parts of 55 which are shown in the figures, is formed in sections or lengths each of which is formed of a lower steel or other metal plate or sheet bent to form the bottom *a* and to provide upwardly turned flanges *b* *c* forming 60 the front and rear walls of the section and an upper steel or other metal plate or sheet bent to form the top *d* of the section and upwardly turned flanges *e* *f* at the front and rear riveted to the front *b* and back *c* 65 of the section. The sections are connected together end to end by means of angle bars *g* *g* riveted on the bottoms *a* and flanged brackets *h* *i* riveted on the front and rear and bolted together by bolts passed through 70 the adjacent angle bars *g* *g* and brackets *h* *i* and transverse plates *j* of which one is shown in Fig. 2 placed between the opposed sets of angle bars *g* *g* and brackets *h* *i* to stiffen the sections when the nuts upon the 75 connecting bolts are tightened. The connected sections of the carriage form a continuous box girder.

The connection of the connected sections to the square of the self acting mule and the 80 completion of the section most remote from the square at the outer ends are effected in any manner convenient. For example angle bars and brackets similar to those shown in Fig. 2 but preferably extending over greater 85 surfaces of the sections to which they are applied, may be provided upon the ends of the sections to adjoin the square and the sections most remote from the square may be provided at the outer ends directed away 90 from the square with metal plates of appropriate form attached by means of angle bars or brackets. *k* *k* are plates with flanges *l* inclined downwards to the rear provided according to this invention to serve as rests 95 for the spindle rails or boxes *m*. The plates *k* are riveted to the fronts *b* of the sections of the carriage and the rearwardly and downwardly inclined flanges *l* are formed so as to be at the height appropriate to the 100 position to be occupied by the spindle rails or boxes *m*. The plates *k* are shown as

- riveted to the fronts *b* of the sections of the carriage by means of rivets *n* serving only for the attachment of the plates *k* so that if it should be desirable to substitute for the 5 plates *k* shown other similar plates with flanges *l* at a different height, the rivets *n* securing them can be easily removed without interference with the fastening of any parts other than the plates *k* but, if it be convenient 10 in any cases, the plates *k* may be secured by the rivets used in securing together the front *b* and top *d* of the section of a carriage or some of them. The plates *k* are shown as presenting plane front surfaces 15 but, if desirable in any case, for the sake of greater stiffness in the plates *k* and consequent stiffening to the carriage front or for any other reason, the plates *k* may be jogged to present on each face parts in two 20 approximately parallel planes so that the upper parts will be brought further towards the front or further towards the rear of the carriage than in the case shown in the drawing. 25 In Figs. 3, 4 and 5, illustrated examples of jogging are shown. Fig. 4 shows a spindle rail rest *z* jogged at *y* so that each face presents parts in two parallel planes, the upper part being further to the rear than the lower part. Fig. 3 shows such a spindle rail rest *z* 30 riveted to the front wall of a mule carriage section *u*. Fig. 5 shows a spindle rail rest jogged at *w* so that each face presents parts in parallel planes, the upper part being further forward than the lower part. 35 What I do claim as my invention and desire to secure by Letters Patent is:—
  1. In a carriage as set forth, a separable plate of metal riveted to the front of the carriage to extend vertically thereon and upwardly therefrom at an appropriate height above the place of attachment and furnished with a rearwardly extending inclined top flange, and serving in the completed carriage as a rest for the spindle rails or spindle boxes. 40
  2. In a carriage as set forth, a separable plate of metal riveted to the front of a section of the carriage to extend vertically thereon and upwardly therefrom at an appropriate height above the place of attachment and furnished with a rearwardly extending inclined top flange, and serving in the completed carriage as a rest for spindle rails or spindle boxes. 45
  3. In a carriage as set forth, a separable plate of metal riveted to the front of sections of the carriage to extend vertically thereon and upwardly therefrom at an appropriate height above the place of attachment and furnished with a rearwardly extending inclined top flange, and serving in the completed carriage as a rest for spindle rails or spindle boxes. 50
  4. In a carriage as set forth, separable plates of metal riveted to the front of the carriage to extend vertically thereon and upwardly therefrom at an appropriate height above the place of attachment and each furnished with a rearwardly extending inclined top flange, and serving in the completed carriage as a rest for spindle rails or spindle boxes. 55
  5. In a carriage as set forth, separable plates of metal riveted to the front of sections of the carriage to extend vertically thereon and upwardly therefrom at an appropriate height above the place of attachment and each furnished with a rearwardly extending inclined top flange, and serving in the completed carriage as a rest for spindle rails or spindle boxes. 60
  6. In a carriage as set forth, a separable plate of metal riveted to the front of the carriage to extend vertically thereon and upwardly therefrom at an appropriate height above the place of attachment and furnished with a rearwardly extending inclined top flange, and serving in the completed carriage as a rest for spindle rails or spindle boxes. 65
  7. In a carriage as set forth, a separable plate of metal riveted to the front of a section of the carriage to extend vertically thereon and upwardly therefrom at an appropriate height above the place of attachment and furnished with a rearwardly extending inclined top flange, and serving in the completed carriage as a rest for spindle rails or spindle boxes. 70
  8. In a carriage as set forth, a separable plate of metal riveted to the front of sections of the carriage to extend vertically thereon and upwardly therefrom at an appropriate height above the place of attachment and furnished with a rearwardly extending inclined top flange, and serving in the completed carriage as a rest for spindle rails or spindle boxes. 75
  9. In a carriage as set forth, separable plates of metal riveted to the front of the carriage to extend vertically thereon and upwardly therefrom at an appropriate height above the place of attachment and each furnished with a rearwardly extending inclined top flange, and serving in the completed carriage as a rest for spindle rails or spindle boxes. 80
  10. In a carriage as set forth, separable plates of metal riveted to the front of sections of the carriage to extend vertically thereon and upwardly therefrom at an appropriate height above the place of attachment and each furnished with a rearwardly extending inclined top flange, and serving in the completed carriage as a rest for spindle rails or spindle boxes. 85
  11. In a carriage as set forth, a separable plate of metal riveted to the front of the carriage to extend vertically thereon and upwardly therefrom at an appropriate height above the place of attachment and furnished with a rearwardly extending inclined top flange, and serving in the completed carriage as a rest for spindle rails or spindle boxes. 90
  12. In a carriage as set forth, a separable plate of metal riveted to the front of a section of the carriage to extend vertically thereon and upwardly therefrom at an appropriate height above the place of attachment and furnished with a rearwardly extending inclined top flange, and serving in the completed carriage as a rest for spindle rails or spindle boxes. 95
  13. In a carriage as set forth, a separable plate of metal riveted to the front of sections of the carriage to extend vertically thereon and upwardly therefrom at an appropriate height above the place of attachment and furnished with a rearwardly extending inclined top flange, and serving in the completed carriage as a rest for spindle rails or spindle boxes. 100
  14. In a carriage as set forth, separable plates of metal riveted to the front of the carriage to extend vertically thereon and upwardly therefrom at an appropriate height above the place of attachment and each furnished with a rearwardly extending inclined top flange, and serving in the completed carriage as a rest for spindle rails or spindle boxes. 105
  15. In a carriage as set forth, separable plates of metal riveted to the front of a section of the carriage to extend vertically thereon and upwardly therefrom at an appropriate height above the place of attachment and furnished with a rearwardly extending inclined top flange, and serving in the completed carriage as a rest for spindle rails or spindle boxes. 110
  16. In a carriage as set forth, separable plates of metal riveted to the front of sections of the carriage to extend vertically thereon and upwardly therefrom at an appropriate height above the place of attachment and furnished with a rearwardly extending inclined top flange, and serving in the completed carriage as a rest for spindle rails or spindle boxes. 115
  17. In a carriage as set forth, separable plates of metal riveted to the front of the carriage to extend vertically thereon and upwardly therefrom at an appropriate height above the place of attachment and each furnished with a rearwardly extending inclined top flange, and serving in the completed carriage as a rest for spindle rails or spindle boxes. 120
  18. In a carriage as set forth, separable plates of metal riveted to the front of a section of the carriage to extend vertically thereon and upwardly therefrom at an appropriate height above the place of attachment and furnished with a rearwardly extending inclined top flange, and serving in the completed carriage as a rest for spindle rails or spindle boxes. 125
  19. In a carriage as set forth, separable plates of metal riveted to the front of sections of the carriage to extend vertically thereon and upwardly therefrom at an appropriate height above the place of attachment and each furnished with a rearwardly extending inclined top flange, and serving in the completed carriage as a rest for spindle rails or spindle boxes. 130

thereon and upwardly therefrom at an appropriate height above the place of attachment and each furnished with a rearwardly extending inclined top flange, and serving

- 5 in the completed carriage as a rest for spindle rails or spindle boxes, the vertical parts of said plates being jogged to present on each face parts in two approximately parallel planes.

In testimony, that I claim the foregoing 10 as my invention, I have signed my name in presence of two witnesses, this eighth day of February 1921.

HENRY PLATT HALL.
